US00D910427S

(12) **United States Design Patent** (10) **Patent No.:** **US D910,427 S**
Yang (45) **Date of Patent:** **** Feb. 16, 2021**

(54) **FASTENER**

(71) Applicant: **GUANGZHOU DIYANG CULTURAL DIFFUSION CO., LTD,**
 Guangzhou (CN)

(72) Inventor: **Songyao Yang**, Guangzhou (CN)

(73) Assignee: **GUANGZHOU DIYANG CULTURAL DIFFUSION CO., LTD,**
 Guangzhou (CN)

(**) Term: **15 Years**

(21) Appl. No.: **29/736,112**

(22) Filed: **May 27, 2020**

(51) **LOC (13) Cl.** **08-08**

(52) **U.S. Cl.** **USPC D8/382**

(58) **Field of Classification Search**

USPC D8/16, 19, 88, 94, 308, 309, 341, 349,
 D8/354, 356, 381, 382, 387
 CPC .. F16B 5/00; F16B 5/06; F16B 21/125; A47B
 97/00; A47B 2097/008; Y10T 24/31

CLAIM

The ornamental design for a fastener, as shown and described.

DESCRIPTION

FIG. 1 is a perspective view of a fastener showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an exploded view thereof;

FIG. 10 is an enlarged view of portion 10 shown in FIG. 1; and,

FIG. 11 is an enlarged view of portion 11 shown in FIG. 2.

1 Claim, 11 Drawing Sheets
